US00D873175S

(12) **United States Design Patent** (10) **Patent No.:** **US D873,175 S**
(45) **Date of Patent:** **** Jan. 21, 2020**

(54) **DRONE**

(71) Applicant: **Shenzhen Hubsan Technology Co., Ltd.**, Shenzhen (CN)

(72) Inventor: **Guangjun Li**, Shenzhen (CN)

(73) Assignee: **Shenzhen Hubsan Technology Co., Ltd.**, Shenzhen (CN)

(**) Term: **15 Years**

(21) Appl. No.: **29/648,683**

(22) Filed: **May 23, 2018**

(51) LOC (12) Cl. **12-06**

(52) U.S. Cl.

USPC **D12/16.1**; D12/328

(58) **Field of Classification Search**

USPC D12/319-345, 1-4, 16.1, 214;
D21/436-454; D30/160

(57) **CLAIM**

The ornamental design for a drone, as shown and described.

DESCRIPTION

FIG. 1 is a perspective view of a drone in an extended mode embodying the new design;

FIG. 2 is a front view thereof;

FIG. 3 is a back view thereof;

FIG. 4 is a side view thereof;

FIG. 5 is another side view thereof;

FIG. 6 is a top view thereof;

FIG. 7 is a bottom view thereof;

FIG. 8 is another perspective view of the drone in a folded mode embodying the new design;

FIG. 9 is a front view of the drone in folded mode thereof;

FIG. 10 is a back view of the drone in folded mode thereof;

FIG. 11 is a side view of the drone in folded mode thereof;

FIG. 12 is another side of the drone in folded mode view thereof;

FIG. 13 is a top view of the drone in folded mode thereof; and,

FIG. 14 is a bottom view of the drone in folded mode thereof.

In the drawings, the broken lines depict unclaimed subject matter only and form no part of the claimed design.

1 Claim, 14 Drawing Sheets
